UNITED STATES PATENT OFFICE.

RALPH W. MARTIN, OF BELLEVUE BOROUGH, PENNSYLVANIA.

MOVING-PICTURE MACHINE.

1,241,869.

Specification of Letters Patent.

Patented Oct. 2, 1917.

Application filed September 8, 1915. Serial No. 49,510.

To all whom it may concern:

Be it known that I, RALPH W. MARTIN, a citizen of the United States, and residing in the borough of Bellevue, in the county 5 of Allegheny and State of Pennsylvania, have invented or discovered new and useful Improvements in Moving-Picture Machines, of which the following is a specification.

My invention consists of new and useful 10 improvements in projectors or moving picture machines.

More particularly, my invention comprises novel means for imparting intermittent travel to the film as it passes the 15 framing gate, and also a new and improved shutter mechanism.

Novel features of construction and arrangement of parts will appear from the following description.

20 In the accompanying drawings, which are intended merely to illustrate the principles of my invention and not to limit the scope of the same to the structure shown, Figure 1 is a perspective showing my invention applied to a projector, parts of the latter being omitted for the sake of clearness; Fig. 2 is a diagrammatic view illustrating the relative rotary movements of the constant and variable speed shafts, and Fig. 3 is a similar 30 view illustrating the relative movements of the variable speed shaft and the rocking shaft.

The following is a detailed description of the drawings, reference being first had 35 to Fig. 1.

A represents the frame or bed plate of the projector provided with two pits 1 to give clearance for the crank arms and wrist pins. 2 is a forwardly extending bracket mounted 40 on the bed and provided with transverse journal boxes 3 and 4, and a third journal box 5 on the angular extremity of said bracket.

B is the power shaft, journaled in box 3 45 and rotated by any convenient means, as hand crank 6, at substantially constant speed and in the direction indicated by the arrow.

7 is a relatively large gear rigidly mounted on the other end of shaft B.

50 8 is a smaller gear, meshing with and in the rear of gear 7, and 9 is a short shaft upon one end of which said gear 8 is rigidly mounted and which is journaled in a box 10 on the bed A. It is evident that shaft 55 9 will be rotated at constant speed in the direction shown by the arrow.

The other end of shaft 9 is provided with a crank arm 11 provided with a wrist pin 12. Clearance is provided for said crank arm and wrist pin by one of the pits 1. 60

13 is a second short shaft mounted in journal box 14 on bed A and in a parallel plane with but to the rear of shaft 9. One end of shaft 13 is provided with a longitudinally slotted crank arm 15 whose slot 65 is engaged by the wrist pin 12.

It is evident that the rotation of the shaft 9 at constant speed will result in the rotation of the shaft 13 at variable speed in the same direction. 70

Referring now to Fig. 2, the smaller circle represents the path of rotation of the wrist pin 11 whose center is the shaft 9, while the larger circle represents the path of rotation of the crank arm 15 whose center is the 75 shaft 13, the dotted line *a* between the centers 9 and 13 representing the distance between the axes of said shafts. The length of said line must necessarily be less than the radius of the smaller circle but may be any 80 length less than the latter, the length of the line controlling the variation in the speed of rotation of the shaft 13.

The smaller circle is shown divided into equal arcs to indicate constant speed of rotation while the larger circle is divided into an equal number of arcs of varying length, in radial alinement with the arcs of the smaller circle, to indicate the variations in speed. 85

The other end of shaft 13 is provided with a crank arm 16 having a wrist pin 17 for which clearance is provided by the second pit 1. The crank arm 16 is shown extending in the opposite direction from that of 95 crank arm 15 of the same shaft but may be set at any angle that may be desired. The maximum of effect, however, is produced by opposing said crank arms, as shown.

18 is a third short shaft journaled in a 100 box 19 on the bed A in a parallel plane with shafts 9 and 13 but in advance thereof.

One end of shaft 18 is provided with a longitudinally slotted crank arm 20 whose slot is engaged by the wrist pin 17. It is 105 evident that the rotation of the shaft 13 will result in imparting a rocking motion to the shaft 18.

Referring now to Fig. 3, the circle indicates the path of the wrist pin 17, its variable 110 speed being indicated by the arcs of different length marked on the circle.

It will be noticed that the arcs on the circle in Fig. 3 vary in a manner reverse to those in the large circle in Fig. 2, owing to the fact that the position of the crank 5 arm 16 is the reverse of that of crank arm 15.

18 represents the rocking shaft and the dotted line *b* indicates the distance between the axes of the two shafts, said distance being necessarily greater than the radius of 10 the circle to produce the rocking motion in the shaft 18.

The tangential lines *c* and *d*, extending from the axis of the shaft 18 represent the upper and lower limits of the rock of the 15 crank arm 20. While the wrist pin 17 is rotating in the direction of the arrow, it is evident that the upward movement of the crank arm 20 is more rapid than its downward movement.

20 21 is a crank arm on the other end of the rock shaft 18, shown set opposite to the crank arm 20. It is evident that the downward rock of the crank arm 21 is at a faster speed than its upward rock. 22 is a wrist 25 pin mounted on said crank arm 21 and pivotally engaging the upper end of a pitman 23 whose lower end is pivotally attached to the dog arm 24 intermediate of the ends of the latter.

30 25 is the framing lever mounted intermediate of its ends on the bed A by means of a threaded stud 26 extending horizontally from the latter. Said framing lever is held rigidly at any desired angle by means of a 35 clamp nut 27 screwed upon the stud 26, against the framing lever.

The forward end of the framing lever is provided with a pivot pin 28 which engages the pierced rear end of the dog arm 24.

40 The forward end of the dog arm 24 is provided with the usual cylindrical dog C.

D is the film sprocket rigidly mounted on the power shaft B parallel with the dog C.

E is the film passing down through the 45 gate F, under the dog C and over the sprocket D. G represents the lens.

The operation of the device is as follows: The shaft B is turned at constant speed to 50 rotate the gear 7 in the direction of the arrow, imparting rotation at constant speed in shaft 9, rotation at variable speed in shaft 13, and a rocking motion in shaft 18, causing the dog C to be alternately raised and lowered, the speed of depression being greater 55 than that of elevation. Meanwhile, the sprocket D is rotated, drawing the film E over the same at a constant speed.

The up and down movement of the dog, working in the loop of the film below the 60 gate, as shown in Fig. 1, acts in conjunction with the sprocket to move the film through the gate by successive steps. Thus when the dog descends with a rapid movement, it pulls down the film loop and thus draws the film 65 rapidly through the gate, but when the dog

ascends at a less rate of speed, it releases its pressure on the film and the latter is stationary at the gate while the picture is being projected on the screen. However during the upward movement of the dog, the 70 sprocket takes up the excess loop of the film below the dog and maintains the film in light contact with the dog, so that when the dog begins its next descent, it is in contact with the film and therefore merely pushes the film downwardly without striking against it. Thus noise and shock are avoided and consequently no injury is caused to the film or the projector mechanism. 75

This improved result is due to the slower 80 upward movement of the dog, enabling the sprocket to take up the slack in the film loop as the dog rises.

The framing of the film is accomplished 85 by adjusting the angle of framing lever 25, thus regulating the path of movement of the dog. The dog will cause the film in the gate to be advanced or retarded in accordance with the position in which the dog is adjusted by means of the framing lever, thus permitting the film to be properly framed in the 90 gate.

Referring now to the shutter mechanism, 95 29 is a shaft journaled in the box 5 and having rigidly mounted on its outer end the shutter blade H, normal to its shaft and adapted to cut through the light beam in front of the lens G. Said blade is preferably sector shaped and not of more than 130° in extent. 100

The inner end of shaft 29 is provided with a beveled gear 30 which meshes with a similar gear 31 on a shaft 32 journaled in the box 4. The outer end of the shaft 32 is provided with a small gear 33 in mesh with the 105 large gear 7, whereby a rotary movement is imparted to the shutter H.

The ratio and assemblage of the gears is such that the shutter completes three revolutions to every round trip or complete cycle 110 of the dog, passing in front of the lens while the dog is descending and drawing the film through the gate, and also passing before the lens twice while the film is stationary.

Thus the same effect on the screen is produced as by the use of the conventional three blade shutter but by the use of but one blade a larger percentage of light is allowed to reach the screen. The blade being not more than 130° in extent, substantially two-thirds 115 of the light from the lens reaches the screen.

Although, for the sake of clearness, I have minutely described the construction shown in the drawings, I do not wish to limit myself thereby, but claim broadly:— 120

1. In a moving picture machine, the combination with a moving picture film, of a gate through which said film passes, a rotary sprocket engaging said film and drawing the same through said gate, an adjustable fram- 125 130

ing lever, a swinging film dog pivotally mounted on said framing lever and engaging said film between the gate and the sprocket, and means for imparting a rocking motion 5 to said dog whereby it intermittently pulls said film through said gate.

2. In a moving picture machine, the combination with a moving picture film, of a gate through which said film passes, a rotary sprocket engaging said film and drawing the same through said gate, an adjustable framing lever, a swinging film dog pivotally mounted on said framing lever and engaging said film between the gate and 10 the sprocket to pull said film intermittently through said gate, and a rocking member actuating said dog and moving more rapidly in one direction than in the other whereby the looping movement of said dog is quicker 15 than its retracting movement and said sprocket is enabled to take up slack in the film, for the purposes described.

3. In a moving picture machine, the combination with a moving picture film, of a gate through which said film passes, a rotary sprocket engaging said film, a rotating shaft, a second shaft receiving rotation at variable speed from said first shaft, a third shaft rocked by said second shaft, and a 20 looping dog engaging the film between said 25

gate and said sprocket rocked by said third shaft.

4. In a moving picture machine, the combination with a moving picture film, of a gate through which said film passes, a 35 sprocket engaging said film and drawing it through said gate, a constant speed shaft, a second shaft, a variable speed crank connection between said shafts, a third shaft, a rocking crank connection between said sec- 40 ond and third shafts, and a looping dog actuated by said third shaft and engaging said film, for the purpose described.

5. In a moving picture machine, the combination with a moving picture film, of a 45 gate through which said film passes, a sprocket engaging said film and drawing it through said gate, a constant speed shaft, a second shaft, a variable speed crank connection between said shafts, a third shaft, a 50 rocking crank connection between said sec- ond and third shafts, a rocking looping dog actuated by said third shaft and engaging said film, and means whereby the looping movement of said dog is at greater speed 55 than its retracting movement, for the purpose described.

Signed at Los Angeles, California, this 31st day of August, 1915.

RALPH W. MARTIN.
